UNITED STATES PATENT OFFICE.

HENRY G. FECHTEL, OF ST. LOUIS, MISSOURI.

DESIGN FOR A BOX-SUPPORT FOR TRICYCLE-WAGONS.

SPECIFICATION forming part of Design No. 30,734, dated May 9, 1899.

Application filed March 27, 1899. Serial No. 710,669. Term of patent 7 years.

To all whom it may concern:

Be it known that I, HENRY G. FECHTEL, a citizen of the United States, residing in the city of St. Louis, State of Missouri, have invented and produced a new and original Design for a Box-Support for Tricycle-Wagons, of which the following is a specification.

Figure I is a side elevation of my new design for the box-support for tricycle-wagons. Fig. II is a bottom plan view.

As seen in the drawings, the leading or essential feature of my new design for the box-support for a tricycle-wagon consists of the perforated portion 2, the portion 3, extending downwardly from the forward end of the portion 2, the portion 4, extending forwardly

from the lower end of the portion 3, the portion 5, extending in a curved line upwardly and forwardly from the forward end of the portion 4, the tubular portion 6, extending up and down from the forward end of the portion 5, and the portions 7 and 8, extending from opposite sides of the portion 5.

I claim—

The design for a box-support for a tricycle-wagon, substantially as herein shown and described.

HENRY G. FECHTEL.
